CLAIM

The ornamental design for ventilator system for a toilet, as shown and described.

DESCRIPTION

FIG. 1 is a top, front perspective view of a ventilator system for a toilet showing my new design;

FIG. 2 is a side elevational view thereof as seen from the right side of FIG. 1;

FIG. 3 is a bottom plan view thereof;

FIG. 4 is a top plan view thereof;

FIG. 5 is a rear elevational view thereof;

FIG. 6 is a side elevational view thereof as seen from the side opposite that shown in FIG. 1; and,

FIG. 7 is an end elevational view thereof as seen from the left end of FIG. 1.

FIG. 1

FIG. 7
